UNITED STATES PATENT OFFICE.

GEORGE W. ANDERSON, OF BENONA TOWNSHIP, OCEANA COUNTY, MICHIGAN.

GAME APPARATUS.

1,342,884.

Specification of Letters Patent. Patented June 8, 1920.

Application filed August 8, 1919. Serial No. 316,011.

To all whom it may concern:

Be it known that I, GEORGE W. ANDERSON, a citizen of the United States, residing at Benona township, in the county of 5 Oceana and State of Michigan, have invented new and useful Improvements in Game Apparatus, of which the following is a specification.

The present invention relates to game 10 apparatus; and its object is to provide novel apparatus wherewith a game may be played.

This object is attained by, and the invention finds preferably embodiment in, the 15 game apparatus hereinafter described and illustrated by the accompanying drawings, in which:

Figure 1 is a top plan view of a game board, with some of the playing pieces in 20 place thereon;

Fig. 2 is a vertical section (enlarged) of a portion of the same taken on a plane corresponding to line 2—2 of Fig. 1;

Fig. 3 is a top plan view (much enlarged) 25 of one of the upwardly extending members of the game board;

Fig. 4 is a like view of a modified form thereof; and

Fig. 5 is a view of one of the playing 30 pieces.

In the embodiment of the invention chosen for illustration by the drawings and for detailed description in the body of this specification, the game board 1, preferably 35 provided with an upwardly extending peripheral rim 2, displays a plurality (25 in the form illustrated) of spaced markings. Means are provided for outlining 40 markings having adjacent threes of such markings at their angles. Preferably these markings and such means are, as illustrated, the following:

The spaced markings in the construction shown are the short posts or upwardly extending members 3, disposed in rows and 45 cross rows rectangularly arranged. Each said member is provided with sockets 4 angularly spaced and extending radially toward the adjacent members. In order that 50 the sockets may extend toward all the adjacent members, eight of such sockets in each member are provided.

In Figs. 1, 2 and 3, these members have upward extensions 5 of less diameter than the body portion of the members; while in 55 the modified form shown in Fig. 4, such upward extension of the member 3 is omitted, the sockets 4 extending uninterruptedly across the top face of the members. The means for outlining triangles is preferably 60 the playing pieces 6, being elongated bars or rods, which are adapted to be seated at their ends in the sockets of the adjacent members, as seen in Fig. 1 and particularly in Fig. 2.

The game, which I have called "The World's League of Nations," is played with this apparatus as follows: The board represents the world and the triangles outlined thereon as hereinafter explained represent 70 the nations. The first player places a playing piece in the sockets of any adjacent pair of members, thus laying it in a direction parallel to the side of the board or diagonally thereto, as he may desire. The second 75 player then places another playing piece in the sockets of any adjacent member. The players proceed turn about in this way, each player's object being to place in the socket the third playing piece which completes the outlining of a triangle, such as is shown at 7 in Fig. 1. The player who thus completes a triangle, "adds a new nation to the league." If the playing piece placed by a player completes a triangle and 85 also forms the second side of another triangle, he may continue to place pieces as long as they complete triangles, whereupon he must place another piece. The player 90 who completes the most triangles wins the game.

It will be seen that a greater or less number of spaced markings or members 3 may be displayed on the game board and that two or more persons may play in the same 95 game; and also that the game may be played by providing the board with spaced markings in any form and by providing any means for connecting the same to form triangles—all of which is within the purview of my invention.

The invention being intended to be pointed out in the claim, is not to be limited to or by details of construction of

the particular embodiment thereof hereinbefore described or shown by the drawings.

I claim:

In a game apparatus; a game board having a plurality of upwardly extending members, each having eight angularly spaced sockets extending radially toward

the adjacent members; elongated playing pieces adapted to be seated in the sockets of adjacent members.

In testimony whereof I have hereunto set my hand at Grand Rapids, Michigan, this fourth day of August, 1919.

GEORGE W. ANDERSON.
